S. A. BISEY.
LINE SLUG CASTING MACHINE.
APPLICATION FILED SEPT. 4, 1920.

1,423,388.

Patented July 18, 1922.

UNITED STATES PATENT OFFICE.

SUNKER ACQ. BISEY, OF NEW YORK, N. Y.

LINE-SLUG-CASTING MACHINE.

1,423,388.

Specification of Letters Patent. Patented July 18, 1922.

Application filed September 4, 1920. Serial No. 408,298.

To all whom it may concern:

Be it known that I, SUNKER A. BISEY, a subject of the King of Great Britain, and a resident of New York city, county and State 5 of New York, have invented certain new and useful Improvements in Line-Slug-Casting Machines, of which the following is a specification.

My invention relates to the casting of line 10 slugs and the object of the invention is to enable a single mold type casting machine to be used for the production of continuous unitary lengths of typographical matter.

The invention involves a number of novel 15 features including particularly a special method of permanently interlocking succeeding sections cast in the mold and the casting of the sections against a composed matrix, which remains in engagement with 20 and travels along with the cast portion of the line slug.

These and other features of the invention will appear more fully as the specification proceeds.

25 The invention is particularly adaptable to a type, lead and rule casting machine like that disclosed in my companion application, Serial No. 164,199, and for that reason I have disclosed the same as applied 30 to a machine of that character, but I wish it understood that the invention is by no means limited to that particular machine, and further, that the structure may be modified as regards the present disclosure without departure from the true spirit and scope of 35 the invention.

In the accompanying drawing:

Figures 1 and 2 are vertical sectional views taken through the mold chamber of 40 the machine, Figure 1 being taken on substantially the plane of line 1—1 of Figure 2, and conversely, Figure 2, being taken on substantially the plane of line 2—2 of Figure 1.

45 Figure 3 is a transverse sectional view similar to Figure 1 with the sliding matrix carrier removed and the top and bottom type face gages set together to cast a blank line slug.

50 Figure 4 is a detached perspective view of the matrix carrier, illustrating the connection of the cast sections thereto during the casting process.

Figure 5 is a composite view illustrative

of different cross sectional forms which can 55 be produced in the mold.

Figure 6 is a plan view, illustrating the permanent integration of the cast sections.

Figure 7 is a detail sectional view, illustrating the additional interlock obtained 60 where the cast sections overflow the matrices.

In the machine disclosed, the mold chamber, as indicated at 10 in Figure 2, is initially defined by upper and lower opposed horizontal mold blocks 11 and 12, and side walls 65 formed by the vertical slides 13 and 14. When the first section is cast, the slide 13 which operates in the upper mold block is lowered to cooperate with the lower mold block 12, and after this first section is cast, 70 the slide is raised to the position indicated and stands there until the casting of the slug is completed. After each section is cast, the slide 14 which operates in the lower mold block 12, is retracted to permit a pusher 75 15 to enter the thus opened side of the mold chamber and to expel the casting therefrom. The mechanism by which these slides are thus operated is not disclosed and may be similar to that shown in the application referred to.

The metal may be introduced into the mold chamber at the back through a jet opening as indicated at 16, to produce the 85 castings 17.

80 The permanent interlock between the cast sections is accomplished by providing the slide 14 with a vertical undercut rib 18 on the mold face thereof, which forms an undercut channel or dove-tail groove in the adjacent side of the molded product, as indicated at 19 (see particularly Figure 4).

90 The upper and lower mold blocks, as shown in Figure 2, form in effect a packing channel at the left of the mold chamber 95 receiving the cast product as it is advanced from the mold chamber. After the first section is cast, and the slide 13 is withdrawn, the front wall of the mold is formed by the rear face of the casting just made 100 and as this is the side which has the undercut groove in it, the metal is flowed into this undercut groove and the sections are thereby permanently and fixedly interlocked.

105 In casting a typographical line slug, the matrices, which I have shown in detail at 20 in Figure 4, are composed in a holder or carrier 21 which is then slidingly engaged in

a guide-way 22 extending across the front of the mold chamber. I have illustrated this carrier in the form of an open frame, having ribs 23 at the upper and lower edges thereof 5 engaging in the grooves 24 provided at the top and bottom of the guide-way and have shown the matrices as held in said frame by being engaged over the ribs 25 which are interrupted at one end of the frame, as indicated at 26, to permit the matrices being slipped laterally into the frame. The matrices when composed in the desired order and properly spaced, as by means of the blanks 27, may be held by a clamp screw 10 15 28 arranged to bear on the end matrix.

As the casts are made, the metal congealing in the depressions of the matrices forms a temporary interlock between the cast portion of the slug and the matrix carrier, 20 thereby causing the matrix carrier to advance in step, and as a unit with the slug being cast. The matrices thus remain in contact with the casting during the entire operation, giving the metal ample time to 25 set and enabling the work to proceed rapidly and smoothly. When the line is cast, the slug may be separated from the matrix, it being convenient for this purpose to entirely 30 remove the matrix holder with the slug from the machine.

Means may be provided for stopping the machine or for giving a suitable indication when the slug is completed. Thus, I have indicated at 29 a switch controlling a power 35 or signal circuit 30 and having an arm 31 standing in the path of travel of the matrix carrier and arranged to be operated thereby when the slug casting is completed. This switch mechanism may be adjustable, as I 40 have indicated, to enable the device to be set for line slugs of different length.

The invention is particularly suited to the casting of "oversize" type face. This is accomplished by enlarging the mold cavity 45 at the matrix end by means consisting in the illustration of opposed upper and lower gages 32 and 33, slidingly supported in the upper and lower mold blocks and adapted to be advanced or retracted by means of the 50 thumb turns 34, 35 which operate pinions 36 in engagement with racks 37 carried by such slides. These gage slides are further shown as secured in their adjusted relations by the set screws 38.

55 In Figure 1, the lower gage slide 33 is indicated as retracted to produce an overhang at the lower face of the slug. In Figure 3, the lower gage is shown as projected into engagement with the upper gage so as to 60 cut off the forward end of the mold cavity and produce a shortened blank slug such as shown at the left in Figure 5. It will be evident that by retracting both slides, an overhang can be produced at both top and 65 bottom of the slug, as shown at the right in

Figure 5. This ability to enlarge the mold cavity at the matrix end makes it possible to produce various forms of display type and other large units with a mold of only moderate normal size.

When casting with matrices which do not register laterally with the sides of the mold chamber, as when the individual matrices are larger or smaller than the mold chamber, the metal may flow laterally beyond the 70 bounds of the mold chamber, producing an excess, as indicated at 39 in Figure 7. This is of advantage, however, in that the section next cast will interlock with the more or less irregular shaped excess, and thereby produce a bond or interlock directly at the type face. This, with the undercut interlock in the body of the slug, produces a firm, strong 80 slug.

The mold is preferably adjustable, as in 85 my prior application, to enable the casting of different body sizes and this, with the adjustability of the type face gages makes it possible to cast typographical matter in a 90 great many different sizes in a machine of only moderate size. It will be clear that pictorial as well as strictly typographical matter may be cast with this machine and I, therefore, wish it understood that the term "typographical," and in fact, other expressions employed herein are used in a descriptive rather than in a limiting sense, except for such limitations as may be required by the prior art.

Ordinarily, the engagement of the cast 100 portion of the slug with the matrix will be sufficient to provide a driving connection between the two, but in special cases, for instance, with electrotype or half-tone matrix blocks where the depressions are relatively 105 shallow, a positive drive for the matrix holder may be provided, as by equipping the ejector with a spring-pressed pawl 40 arranged to engage with properly spaced notches or teeth 41 on the matrix carrier. 110 In the rearward stroke of the ejector this pawl will simply slide over the toothed rib 23 on the upper edge of the matrix carrier, but on the forward stroke of the ejector, the pawl will take hold of the carrier and insure 115 its traveling along in unison with the ejected portion of the slug.

What I claim is:

1. The process of producing a continuous typographical line slug of indefinite length 120 with a mold of definite and less length which comprises repeatedly casting units in the mold in contact with preceding units and against successive matrices of a composed line of matrices, ejecting the units from the 125 mold as they are cast and automatically advancing the composed line of matrices through the engagement of the cast sections therewith.

2. The process of casting a line slug, which 130

- consists in movably supporting a matrix in position to traverse the open side of a mold, making repeated castings in said mold against successive portions of the matrix, 5 ejecting the cast sections from the mold chamber in a direction corresponding to the direction of travel of the matrix and thereby advancing the matrix in the ejecting operations by the temporary interlock of the 10 cast sections therewith.
3. The process of casting a typographical line slug, which consists in supporting a composed line of matrices in position to traverse the open side of a mold chamber, 15 repeatedly casting in said mold chamber against successive matrices, and ejecting the sections as they are cast from the mold chamber and in the line of travel of the matrices to thereby enable the cast sections to remain 20 in contact with the matrices and to propel the same by reason of their temporary interlock therewith.
4. The process of integrating successively cast sections of a line slug, which consists 25 in casting each of said sections with an undercut groove in one side thereof, positioning such sections to cause the sides therof with the undercut grooves to form a wall of the mold chamber for a subsequent casting 30 and flowing the metal of the subsequent castings against such sides and into the undercut grooves.
5. The process of integrating successively cast portions of a line slug, which consists in 35 casting the undercut element of a dove-tail joint in the rear face of each section cast and flowing the metal of subsequent castings against such rear faces to interlock the same with and to form the companion undercut 40 elements of the dovetail joints.
6. The process of casting a line slug, which consists in casting a unit of definite size against the face of a matrix and allowing the metal casting to overflow the face of the 45 matrix beyond the bounds of the body of the unit and casting subsequent units overlapping and interlocked with such overflow portions at the face of the matrix.
7. The process of casting a line slug, which 50 consists in casting a unit of definite size against the face of a matrix and allowing the metal casting to overflow the face of the matrix beyond the bounds of the body of the unit and casting subsequent units with 55 their bodies interlocked and overlapping and interlocked with such overflow portions at the face of the matrix.
8. In a machine of the character described, a mold chamber open at one end and a matrix carrier mounted to traverse the open end 60 of the mold chamber and free to travel in engagement with sections cast in the mold chamber.
9. In a machine of the character described, 65 a mold chamber open at one end, a matrix carrier mounted to traverse the open end of the mold chamber and free to travel in engagement with sections cast in the mold chamber and means for ejecting the cast sections from the mold chamber and in the line of travel of the matrix carrier. 70
10. In a machine of the character described, a mold chamber having an open end, a matrix carrier mounted to traverse the open end of the mold and control mechanism operable by said matrix carrier upon a predetermined movement thereof. 75
11. In a machine of the character described, a mold chamber having an open end, a matrix carrier mounted to traverse the open end of the mold, control mechanism operable by said matrix carrier upon a predetermined movement thereof and means for setting said control mechanism to operate at different points in the travel of the matrix carrier. 80
12. In a machine of the character described, a mold adjustable to cast individual type of different body sizes and gage mechanism adjustable to determine the size of the type face cast in the mold and means for supporting a matrix at the end of the mold and at the outer side of said adjustable gage mechanism, whereby the casting against the matrix will be governed as to size by the adjustment of such gage mechanism. 85
13. In a machine of the character described, a mold chamber, means for supporting a matrix at the end of said chamber and a gage at the matrix end of the chamber adjustable transversely thereof to vary the size 90 of the type face. 100
14. In a machine of the character described, a mold chamber, means for supporting a matrix at the end of the chamber, gages at the matrix end of the mold chamber and at the opposite sides of said chamber and means for relatively adjusting said gages toward and away from each other. 105
15. In a machine of the character described, a mold chamber, means for supporting a matrix at the end of the chamber, gages at the matrix end of the mold chamber and at the opposite sides of said chamber and means for relatively adjusting said gages toward and away from each other, 110 said gages being adjustable into engagement with each other to cut off the end of the mold chamber. 115
16. In a machine of the character described, an open-ended mold chamber, a transverse guide-way at the open end of the mold chamber, a matrix carrier slidably engaged with said guide-way and means on said carrier for adjustably securing a line of composed matrices therein. 120
17. In a machine of the character described, a mold chamber and a packing channel at one side of and forming a continuation of the mold chamber, a guide-way at the end of the mold chamber and substan- 130

tially parallel to the packing channel, a matrix carrier operating on said guideway and an ejector for ejecting units cast in the mold chamber into the packing channel aforesaid.

5 18. In a machine of the character de-
scribed, a mold chamber defined by opposed
mold blocks and rectangularly arranged
slides operable to close and open the mold
chamber and a matrix carrier freely mov-
10 able past one end of the thus defined mold
chamber.

19. In a machine of the character described, a mold chamber defined by opposed mold blocks and rectangularly arranged 15 slides operable to close and open the mold chamber, a matrix carrier freely movable past one end of the thus defined mold chamber and type face limit gages movable transversely of said mold chamber.

20. 20. A mold for casting fused sectional typographical slugs of indefinite length and consisting of a chamber having three mold walls and a fourth mold wall provided by a previously cast portion of the slug and one
25 end of said mold chamber being closed by a matrix bar traveling with the cast portion of the slug and means for ejecting the cast portions of the slug from the mold chamber.

21. A mold for casting fused sectional typographical slugs of indefinite length and consisting of a chamber having three mold walls and a fourth mold wall provided by a

previously cast portion of the slug and one end of said mold chamber being closed by a matrix bar traveling with the cast portion 35 of the slug.

22. A mold for casting fused sectional typographical slugs of indefinite length and consisting of a chamber having three mold walls and a fourth mold wall provided by a previously cast portion of the slug and one end of said mold chamber being closed by a matrix bar traveling with the cast portion of the slug, said mold including means for ejecting the cast product from the mold chamber and for positively shifting the matrix bar in unison with the ejected cast product.

23. A mold for casting fused sectional typographical slugs, comprising upper and lower mold blocks, a member cooperating therewith to form the third side of the mold cavity and the fourth side of the mold cavity being provided by a previously cast section and a matrix block traveling with the cast portion of the slug, said mold including mechanism by which the cast section is ejected from the mold and the matrix is shifted in unison with the travel of the cast section. 50 55 60

In witness whereof, I have hereunto set
my hand this 3rd day of September, 1920.

SUNKER AOQ. BISEY.
